UNITED STATES PATENT OFFICE.

LEONARD E. WOOD, OF SAN FRANCISCO, AND CHARLES R. COOPER, OF BERKELEY, CALIFORNIA.

SEAL.

SPECIFICATION forming part of Letters Patent No. 739,248, dated September 15, 1903.

Application filed January 7, 1903. Serial No. 138,131. (No model.)

To all whom it may concern:

Be it known that we, LEONARD E. WOOD, residing in the city and county of San Francisco, and CHARLES R. COOPER, residing at 5 Berkeley, county of Alameda, State of California, citizens of the United States, have invented an Improvement in Seals; and we hereby declare the following to be a full, clear, and exact description of the same.

10 Our invention relates to a device for sealing cars, rooms, and receptacles of any sort, and it is especially designed for use upon freight-cars where it is desirable to seal the doors to prevent any removal of or tampering 15 of the goods contained therein.

It consists, essentially, of a flexible metal strap adapted to pass through the hasp and staple or lock of any description by which the door is secured and in a means for securing the ends of said metal strap so that it cannot be opened or removed without showing that it has been tampered with.

Referring to the accompanying drawings, Figure 1 is a view of a blank ready for forming. Fig. 2 shows the ends of the seal separated. Fig. 3 shows the ends in partial engagement. Fig. 4 shows the ends fully interlocked. Fig. 5 shows the seal closed through staples.

30 It is customary to seal the locks of freight-cars and like receptacles by the use of flexible or soft-metal bands, which are passed through the lock or other fastening and the ends are afterward secured together either 35 by a soft-metal seal or by interlocking the ends in such a manner as to prevent their being separated.

It is the object of our invention to improve this latter form of flexible sealing-band and 40 provide a means for readily interlocking the ends and preventing their being again separated.

As shown in the accompanying drawings, A is a flexible metal band of this description, 45 having one end formed with a tongue, as at 2, which projects beyond, and a side projection 3, which may be folded over after the tongue has been bent inwardly upon the part A, the fold covering and inclosing the tongue, 50 and the edge which is folded over may be united with the coincident edge of the part

A by soldering or otherwise closing it hermetically, thus leaving a small opening at the end exterior to the tongue 2. This tongue 2 is sufficiently elastic so that its inner end 55 normally springs out against the folded-over portion 3. The opposite end of the band A has a similar fold or tongue 4, and this may be introduced into the open end between the tongue 2 and the folded-over portion 3, and, 60 being pushed in, the tongue 4 will pass the tongue 2, the ends being temporarily compressed to allow them to thus pass. As soon as the ends have passed each other they will spring out, the one that was introduced springing out against the part A, while the tongue 2 will, as before described, spring out against the folded-over part 3. Then when any pull 65 is brought upon the strap these ends are caused to interlock with each other, one passing 70 within the other, so that it is impossible to separate them.

In order to prevent the introduction of any instrument to temporarily spring the tongues down, and thus allow them to pass each other, 75 we make a small lug or projection 5 upon the inside of the portion A, this lug projecting inward, so as to press upon the tongue 2 and to hold it normally against the inner surface and the folded-over portion 3. This projection 80 5 may be formed in various ways. It may be a separate piece secured upon the inside of the part A, or it may be formed by indenting the part A from the outside, correspondingly bulging this indented portion toward 85 the inside. By this projection pressing constantly upon the tongue it will be impossible to move the latter sufficiently to disengage the two tongues without mutilating the seal, so that any tampering with it will be at once 90 discovered when the car arrives at any point where inspection takes place.

Having thus described our invention, what we claim, and desire to secure by Letters Patent, is—

1. A seal consisting of a flexible strip having tongues folded back outwardly and inwardly respectively upon the opposite ends so as to interlock when brought together, a sheath, covering and inclosing the inwardly-folded tongue at one end and a projection on the inner surface of the sheath adapted to

press upon the interlocking tongues to prevent separation.

2. A seal consisting of a flexible strip having one end folded back to the outside to form 5 an elastic tongue, the other end folded inwardly to form a second elastic tongue, a side section formed with said end adapted to be folded inwardly over the tongue to form an inclosing sheath and an inwardly-projecting 10 lug formed on the outer portion of the band

or strip and adapted to press upon the tongues when interlocked.

In witness whereof we have hereunto set our hands.

LEONARD E. WOOD.
CHARLES R. COOPER.
